UNITED STATES PATENT OFFICE

JOHN E. PRACNY, OF WATERBURY, CONNECTICUT, ASSIGNOR TO THE E. J. MANVILLE MACHINE COMPANY, OF WATERBURY, CONNECTICUT, A CORPORATION OF CONNECTICUT

HEADING MACHINE

Application filed January 24, 1928. Serial No. 249,104.

This invention relates to machines for shaping the ends of cold metal stock by the percussive action of punches and dies, of the class illustrated and described in U. S. patent to Campbell, No. 926,170, June 29, 1909. 5 That patent illustrates a double stroke, open die header, that is, a machine which feeds the end of a rod of stock through opened dies that are then moved transversely to clamp the stock, cut off the desired length and carry the cut piece into line with punches which strike two blows for forming and completing a head on the end of the stock that is exposed beyond the dies, after which the dies are returned and 10 are opened to allow a subsequent feed of stock which ejects the headed blank.

The object of the present invention is to so construct a machine of this type that not only can a head be formed on one end of a long 20 piece of stock but at the same time the other end will be extruded, that is, elongated and reduced in diameter to a size which will permit a thread that will have the same diameter as the original stock to be rolled on the elongated and reduced section.

This object is attained by providing a heading machine with transversely movable open dies for receiving, clamping, cutting and transferring the stock into line with the 30 punches, and with a solid die fixed in line with the punches, which latter die will extrude the inner end of the stock coincidently with the heading of the outer end of the stock, the machine also having means for ejecting the reduced and elongated end of the stock from the solid extruding die.

Extruding is impractical with open dies only; for they separate and fins are formed along the stock under the blows of the 40 punches, and extruding solely with a solid die limits the length of the stock that can be used, results in imperfectly cut ends which causes excessive wear on the extruding die as well as imperfect sizes, and requires a larger 45 machine for the stroke must be longer, which not only increases the cost of the machine but limits the output as there is loss of time in operation with the necessary long stroke.

The combination of open and solid dies allows 50 a long piece of stock to be securely

gripped and firmly supported by the open dies so that its end will be squarely cut and it will not buckle under the impact of the punches when it is headed and forced into the solid extruding die.

In the accompanying drawings only so much of the mechanism necessary to an understanding of the invention as embodied in a double blow heading machine of the class above mentioned is illustrated, and while the drawings show and the following description sets forth a double blow machine for heading and extruding, it is to be understood that the invention may be embodied in a single blow machine and not only be utilized for heading one end and simultaneously extruding the other end of a blank, but may be employed for simply extruding one or both ends of a piece of stock, by the use of either a single punch or two punches, depending upon the shape of the blanks to be produced, the term "heading machine" being used merely as a convenient indication of the class of machines to which the improvement applies.

In the accompanying drawings Fig. 1 shows a plan view of the front end of a heading machine arranged according to this invention, with a portion of the frame cut away to expose the solid cutting off and extruding dies, the open dies with stock fed between them, and the mechanism for moving the open dies transversely for cutting off a length of stock and carrying it into line with the punch and extruding die. Fig. 2 shows on larger scale a transverse section of the frame looking toward the open dies, with these dies clamped together and moved over to heading and extruding position. Fig. 3 is a horizontal section taken through the dies, with the open dies in heading and extruding position. Fig. 4 is a similar view with the open dies in feeding position. Fig. 5 is a horizontal section through the dies, on still larger scale, showing the open dies in feeding position and a headed and extruded blank about to be ejected from the open dies by the entrance of another length of stock.

In the die pocket 1 in the front end of the head of frame 2 are two dies 3, which dies as they are opened to permit the feed

of stock into them and the discharge of the completed blank from them, and are closed to hold the stock tightly clamped while the desired length is cut off and while the punch or punches are operating, are termed "the open dies". These dies are moved transversely in the die pocket in one direction by the action of toggle links 4, the toggle links being straightened by a link 5 actuated from a cam or crank, and returned by a spring 6, as is commonly known and as illustrated in the patent above referred to. The straightening movements of the toggle links are transmitted to the dies through a toggle block 7, plungers 8, plunger plate 9 and filling block 10. When the toggle links are returned the dies are pushed back by a spring 11 which thrusts against a plunger 12 that has a head 13 between which and the dies is a filling block 14, Fig. 1.

The open dies are moved back and forth by this means a distance equal to that between the cutting die opening 15 and the extruding die opening 16, both of which openings are in the fixed plate 17 of hardened steel set in the anvil plate 18. Back of the anvil plate is a filling block 19. The movable dies slide on hardened plates 20 fastened in the bottom of the die pocket, and are held against the anvil plate by retaining guides 21 that are attached to the die cap 22 which is fastened down upon the top of the dies so as to hold them on the bottom plates and against the anvil plate, as they are moved back and forth.

Any common type of stock feed may be employed, that illustrated having rolls 23 which are intermittently rotated by mechanism 24 to feed the required length of stock into the machine, the stock being in the form of a continuous rod or wire 25. With the open dies in feed position and slightly separated the feed rolls push the stock through aligned openings in the frame, the filling block 19, anvil plate 20, the fixed die plate 17 and the open dies until the end of the stock is stopped by the gauge arm 26. This stop arm is oscillated, by the usual mechanism, into the path of the stock as it is fed, and back out of the way after the feed is completed. The open dies are then forced transversely in the die pocket by the toggles, which first close the dies so that they will tightly clamp the stock, and then move the dies so that a length of the clamped stock is cut off between the back face of the open dies and the front face of the fixed cutting die 15, and carried into line with the extruding die 16 and the punch 27, in which position the dies and filling blocks are very tightly clamped together between the thrust plate 28 and the plunger plate 9. With the dies held in this manner the punch comes forward and strikes the stock driving it back so as to force the inner end of the stock into the extruding die 16,

the opening in which is somewhat smaller than the opening in the open dies, and thereby reducing the diameter of and extending the length of a section 29 of the inner end of the stock and at the same time upsetting and forming a head 30 on the outer end of the stock, Fig. 3. If it is a double blow machine as shown in the patent referred to, the first punch may merely initially shape the outer end of the stock and the second punch complete the head on the outer end of the stock.

In line with the extruding die is a pin 31 which is designed to limit the length of the stock that is extruded and subsequently drive the extruded section from the solid extruding die. Back of this pin is a rod 32, the position and action of which is controlled by the lever 33 that is engaged by a stud 34 on a slide 35 which is reciprocated by a link 36 actuated by a cam in the manner common in the class of closed die headers. When the blank is headed by the punch and reduced and lengthened by being driven into the extruding die, the backing pin is in position to be engaged by the inner end of the stock, as shown in Fig. 3. After this operation is completed the pin is driven forward so as to force the extruded end of the blank from the extruding die into the open dies which then carry the blank into line with the incoming length of stock to be fed, as illustrated in Fig. 5. The subsequent feed of stock ejects the finished blank from the open dies and the cycle of operations is repeated.

By means of the combination of open dies, which clamp, sever and carry the stock into line with the punch, and solid extruding die, illustrated, a common header may be used to produce long blanks with heads at one end and with sections reduced for thread rolling at the other end without increasing the size of the machine or reducing its speed of operation. With open dies the stock being clamped tightly the end is cut off more squarely than it is when cut off at the face of a solid die so that the blanks are in better condition for having their inner ends reduced and extruded without excessive wear on the extruding die, and to have their outer ends properly headed by the punch, but it has been found impractical to extrude with open dies only for such dies tend to spread under the impact of the blows of the punch and leave fins on the extruded section. With a solid die only the stock has to be fed completely through it and cut off beyond its face, and the cut pieces transferred by carrying mechanism into line with the punch and then driven back the entire length of the solid die when headed and extruded, and subsequently pushed forward the whole length of the die in order to be ejected, which requires a greater distance between the face of the die and the punch carrying gate, thus necessitating an increase in the

size of the machine, a greater travel for the punch and a longer movement for the ejecting or knock-out pin with a consequent loss of time, than when open dies are used.

5 The invention claimed is:

1. A heading machine having a die pocket, a solid cutting die and a solid extruding die fixed in said pocket, and dies adapted to be opened and closed and moved transversely in the pocket, means for feeding stock through the cutting die and movable dies, mechanism for moving said movable dies across the face of the cutting die and severing a length of the stock and carrying it into line with the extruding die, a reciprocating punch in line with the extruding die and adapted to strike the stock held by the movable dies and drive its inner end into the extruding die, mechanism for ejecting the stock from the extruding die, and means for returning the movable dies into line with the cutting die and allowing the incoming stock to eject the completed blank from the movable dies.

2. A heading machine having a die pocket, a plate containing a cutting die and an extruding die fixed in said pocket, dies adapted to be opened and closed and moved transversely in the pocket, means for feeding stock through the cutting die and movable dies, mechanism for moving said movable dies across the face of the cutting die and severing a length of the stock and carrying it into line with the extruding die, a reciprocating punch in line with the extruding die and adapted to strike the stock held by the movable dies and drive its inner end into the extruding die, mechanism for ejecting the stock from the extruding die, and means for returning the movable dies into line with the cutting die and allowing the incoming stock to eject the completed blank from the movable dies.

3. A heading machine having a die pocket, a solid cutting die and a solid extruding die fixed in said pocket, and dies adapted to be opened and closed and moved transversely in the pocket, intermittently rotated rolls for feeding stock through the cutting die and movable dies, mechanism for moving said movable dies across the face of the cutting die and severing a length of the stock and carrying it into line with the extruding die, a reciprocating punch in line with the extruding die and adapted to strike the stock held by the movable dies and drive its inner end into the extruding die, mechanism for ejecting the stock from the extruding die, and means for returning the movable dies into line with the cutting die and allowing the incoming stock to eject the completed blank from the movable dies.

4. A heading machine having a die pocket, a solid cutting die and a solid extruding die fixed in said pocket, and dies adapted to be opened and closed and moved transversely in the pocket, means for feeding stock through

the cutting die and movable dies, mechanism for moving said movable dies across the face of the cutting die and severing a length of the stock and carrying it into line with the extruding die, a reciprocating heading punch in line with the extruding die and adapted to strike the stock held by the movable dies and simultaneously head its outer end and drive its inner end into the extruding die, mechanism for ejecting the stock from the extruding die, and means for returning the movable dies into line with the cutting die and allowing the incoming stock to eject the headed and extruded stock from the movable dies.

5. A heading machine having a die pocket, a solid cutting die and a solid extruding die fixed in said pocket, and dies adapted to be opened and closed and moved transversely in the pocket, means for feeding stock through the cutting die and movable dies, mechanism for moving said movable dies across the face of the cutting die and severing a length of the fed stock and carrying it into line with the extruding die, a reciprocating punch in line with the extruding die and adapted to strike the stock carried by the movable dies and drive its inner end into the extruding die, a knock-out pin and mechanism for causing the knock-out pin to push the end of the stock from the extruding die, and means for returning the movable dies into line with the cutting die and allowing the incoming stock to eject the completed blank from the movable dies.

6. A heading machine having a die pocket, a cutting die and an extruding die fixed in said pocket, and dies adapted to be moved transversely in the pocket from the cutting die to the extruding die, means for feeding stock through the cutting die and movable dies, mechanism for moving said movable dies across the face of the cutting die and severing a length of the stock and carrying it into line with the extruding die, a reciprocating punch in line with the extruding die and adapted to drive the inner end of the stock into the extruding die, mechanism for ejecting the stock from the extruding die, and means for returning the movable dies into line with the cutting die.

7. A heading machine having a die pocket, a solid extruding die fixed in said pocket, and dies adapted to be opened and closed and moved transversely in the pocket, means for feeding stock through the movable dies, mechanism for causing said movable dies to carry a length of stock into line with the extruding die, a reciprocating punch in line with the extruding die and adapted to drive the inner end of the stock into the extruding die, and mechanism for ejecting the stock from the extruding die and from the movable dies.
